UNITED STATES PATENT OFFICE

99,586

DESIGN FOR A COMBINED HANDLE-BAR STEM AND SPEEDOMETER MOUNTING FOR BICYCLES

Earl E. Pease, Oak Park, Ill., assignor to Battery
Patents Corporation, Chicago, Ill., a corpora-
tion of Illinois

Application March 26, 1936, Serial No. 61,802

Term of patent 14 years

To all whom it may concern:

Be it known that I, Earl E. Pease, a citizen of the United States, residing at Oak Park, in the county of Cook and State of Illinois, have invented a new, original, and ornamental Design for a Combined Handle-Bar Stem and Speedometer Mounting for Bicycles, of which the following is a specification, reference being had to the accompanying drawing, forming a part thereof, in which:

Figure 1 of the drawing is a side view, in ele-

vation, showing my new design; Fig. 2, a front view in elevation the view being taken, as indicated, at line 2 of Fig. 1; and Fig. 3, a plan view the view being taken, as indicated, at line 3 of Fig. 1.

I claim:

The ornamental design for a combined handle-bar stem and speedometer mounting for bicycles, as shown.

EARL E. PEASE.
